Primary Examiner — George D Kirschbaum*Assistant Examiner* — Jennifer Watkins(74) *Attorney, Agent, or Firm* — Merchant & Gould, P.C.(57) **CLAIM**

The ornamental design for a prosthetic socket brim, as shown and described.

DESCRIPTION

FIG. 1 shows a top anterior-lateral perspective view of a prosthetic socket brim;

FIG. 2 shows an anterior side view thereof;

FIG. 3 shows a posterior side view thereof;

FIG. 4 shows a medial side view thereof;

FIG. 5 shows a lateral side view thereof;

FIG. 6 shows a top face view thereof; and,

FIG. 7 shows a bottom face view thereof.

The broken lines illustrate environmental structure and form no part of the claimed design.
